UNITED STATES PATENT OFFICE.

ANDREW M. RANTZ, OF CAMBRIDGEPORT, AND CHARLES L. ENGELHARDT,
OF BOSTON, MASSACHUSETTS.

FASTENER FOR THE MEETING-RAILS OF SASHES.

SPECIFICATION forming part of Letters Patent No. 275,706, dated April 10, 1883.

Application filed October 13, 1882. (No model.)

To all whom it may concern:

Be it known that we, ANDREW M. RANTZ, a citizen of Sweden, now residing at Cambridgeport, in the county of Middlesex and State of Massachusetts, and CHARLES L. ENGELHARDT, a citizen of the United States, residing at Boston, in the county of Suffolk and State of Massachusetts, have jointly invented certain new and useful Improvements in Window-Sash Fasteners; and we do hereby declare that the same are fully described in the following specification and illustrated in the accompanying drawings.

This invention relates to improvements in window-sash fasteners, and it is carried out as follows, reference being had to the accompanying drawings, in which—

Figure 1 represents a plan view of the device shown in a locked position. Fig. 2 represents a front elevation of it shown as locked. Fig. 3 represents a vertical section on the line A B, shown in Figs. 1 and 2. Fig. 4 represents a side elevation of the device shown in the act of locking and securing the sashes together.

Similar letters refer to similar parts wherever they occur in the different parts of the drawings.

In the drawings, *a* represents the lower portion of the outer window-sash, and *b* represents the upper portion of the inner window-sash, as usual. To the sash *a* is secured the striker *a'*, provided on its upright part with a slotted perforation, *a''*, for the reception of the latch-lever, hereinafter to be described. To the sash *b* is secured the plate *c*, provided with vertical bearings *c' c''*, through the upper ends of which passes the screw, pin, or rivet *c'''*, as shown.

d is the latch-lever, journaled on the pin *c'''* between the bearings *c' c''*. The outer end of the latch-lever *d* is provided with a hooked projection, *d'*, adapted to be swung into the slotted perforation *a''* on the striker *a'* when the sashes *a* and *b* are brought in proximity

to each other, and thus to effect a strong and secure lock between them by moving the latch-lever *d* from the position shown in Fig. 4 to the position shown in Fig. 3, which is done by depressing the handle *d''*, that forms a rear extension of the latch-lever *d*, as shown in said figures. For the purpose of automatically retaining the latch-lever *d* in its locked position, as shown in Figs. 1, 2, and 3, we employ the lock cam or lever *h*, hinged at *h'* to the plate *c*, and provided with a thumb-piece, *h''*, by means of which it is operated to be swung back against the rear portion of the latch-lever *d*, as shown in Figs. 1, 2, and 3, and by means of which the latch-lever is prevented from being detached from the striker until the lock cam or lever *h* is swung to one side of the latch-lever *d*, which latter is then automatically caused to swing backward on its fulcrum-pin *c'''* by the influence of a suitable spring-wire, *g*, which is coiled around the pin or screw *c'''*, with its free ends resting against the rear of the vertical bearings *c' c''* and its looped end pressing on the under side of the handle or extension *d''*, as shown in Figs. 3 and 4.

We desire to state that we do not wish to claim as our invention the locking device marked *d''' e e' f f' f'' f'''* in the drawings; but

What we wish to secure by Letters Patent, and claim, is—

In a window-sash fastener, the combination of the latch-lever *d* *d' d''*, bearings *c' c''*, fulcrum-pin *c'''*, spring *g*, and the striker *a' a''* with the locking cam or lever *h* *h' h''*, as and for the purpose set forth.

In testimony whereof we have affixed our signatures in presence of two witnesses.

ANDREW M. RANTZ.
CHARLES L. ENGELHARDT.

Witnesses:

ALBAN ANDRÉN,
HENRY CHADBOURN.
